UNITED STATES PATENT OFFICE.

ARTHUR ROSCH, OF CHARLOTTENBURG, BERLIN, GERMANY, ASSIGNOR, BY MESNE ASSIGNMENTS, TO GENERAL ELECTRIC COMPANY, OF SCHENECTADY, NEW YORK, A CORPORATION OF NEW YORK.

INDUSTRIAL-HEATING ELASTIC-FLUID PRIME-MOVER INSTALLATION.

Application filed November 9, 1925, Serial No. 67,792, and in Germany November 25, 1924.

The present invention relates to elastic-fluid prime-mover installations arranged to provide industrial heating elastic fluid which has performed work in the prime movers, and has for its object the provision of an improved arrangement in an installation of this character whereby heating elastic fluid for industrial uses, such as cooking, boiling, heating and the like, is automatically provided in conjunction with the operation of the installation while maintaining a high operating efficiency.

For a consideration of what is believed to be novel in the invention, attention is now directed to the accompanying drawing, the description thereof, and the appended claims.

In the drawing, the figure is a diagrammatical representation, partly in section, of an elastic-fluid prime-mover installation embodying the invention.

Referring to the drawing, 5 and 6 are elastic-fluid turbines of the multistage type supplied with elastic motive fluid through separate supply conduits 7 and 8 and admission valve means 9 and 10 respectively. The turbines represent any suitable elastic fluid prime movers adapted to supply heating elastic fluid in connection with their operation as will hereinafter appear, and accordingly will hereinafter be referred to as elastic fluid prime movers.

In the present example, prime mover 6 is a smaller or auxiliary unit and is mounted on a common shaft 11 with prime mover 5 which is the larger or main unit of the installation. Prime mover 6 is connected at its exhaust end with a mixing conduit or exhaust header 12 to which it supplies exhaust elastic fluid at a pressure suitable for use in an industrial heating main 13 which taps the exhaust header at 14 to receive said exhaust elastic fluid therefrom.

The exhaust header forms a supply source for the heating main and may be connected with heating elastic fluid supply means other than the exhaust end of the auxiliary prime mover to receive additional heating elastic fluid for delivery to the heating main. In the present example, it is connected for this purpose with the main prime mover between a high pressure section 15 and a low pressure section 16 thereof, as indicated at 17. In the case of the particular

prime mover shown the exhaust header extends through connection 17 into the prime mover in the form of a chamber 18 which directly receives the exhaust from the high pressure section 15 and which is connected with the low pressure section 16 by a conduit 19. The low pressure section exhausts through a suitable exhaust outlet 20. This arrangement permits the exhaust header 12 to receive exhaust elastic fluid from the high pressure section 15 or to deliver exhaust elastic fluid to the low pressure section 16 jointly with the high pressure section, depending upon the pressure in the exhaust header which tends to fluctuate in response to fluctuations in the demand on the heating supply main 13 and in the pressure in supply conduit 8 of the auxiliary prime mover.

Fluctuations in pressure in the exhaust header 12 are met by a pressure regulator 21 which operates a relief valve 22 in response to the pressure changes. The relief valve is located in conduit 19 and controls the admission of elastic fluid to the low pressure section 16 from chamber 18, that is, from the exhaust header. In the present example, the pressure regulator is in the form of a cylinder in which a piston 23 moves in response to pressure supplied beneath it through a pressure pipe 24 connected with the exhaust header. This connection is conveniently made, as shown, with chamber 18 on the admission side of valve 22.

The piston is provided with a sliding piston rod 25 which is pivotally connected, as indicated at 26, with a lever 27, which in turn is pivotally connected, as indicated at 28, with the sliding stem 29 of the valve 22. At 30 is a fulcrum for the lever about which it is moved by the regulator to carry the valve between the open and closed positions. Above the piston is provided a compressed spring 31 which serves to move piston 23 against the pressure acting beneath it, to carry the valve towards the closed position. With this arrangement the low pressure section 16 receives excess elastic fluid from the exhaust header automatically, an increase in pressure in chamber 18 and the exhaust header effecting an increased opening of valve 22 and increased delivery to the low pressure section, and a decrease in pressure causing a corresponding de-

creased opening and decreased delivery to the low pressure section.

Admission valve 9 is also pivotally connected with lever 27 on the opposite side of fulcrum 30 from valve 22, as indicated at 32, through a valve stem 33, so that it is moved with valve 22 in an opposite sense with respect thereto. This provides for admitting an increased amount of elastic fluid 10 through valve 9 as pressure regulator 21 operates to close valve 22 and vice versa, thus more quickly tending to restore normal pressure in the exhaust header. The normal pressure in the exhaust header is determined by the strength of regulator spring 31 in its relation to the piston area and may be made to provide any desired normal pressure.

Admission valve 10 for auxiliary prime mover 6 is controlled by a pressure regulator 34 which operates to maintain a substantially uniform pressure in the supply conduit 8, that is, to admit elastic fluid therefrom in accordance with the pressure therein. The regulator is similar in construction to regulator 21 and like regulator 21 represents any suitable pressure-responsive device for controlling a valve. Although any suitable operating connection may be provided between the regulators and their respective valves, in the present example they are arranged to directly move the valves, regulator 34 being connected with valve 10 after the manner of regulator 21 with valve 22, by a sliding valve stem 35 which is pivotally connected at 36 with a lever 37. The latter is in turn pivotally connected at 38 with a sliding piston rod 39 of the regulator.

Piston rod 39 is connected to and moves 40 with a sliding piston 40, to the lower side of which is supplied pressure from conduit 8, at the admission side of valve 10, by a pressure pipe 41. The piston moves in response to the pressure supplied beneath it, against a compressed spring 42 to carry the valve toward the open position, while the spring tends to move the piston to carry the valve to the closed position. Lever 37 moves on 45 a fulcrum 43 which is located along the lever in spaced relation to pivot connection 36 of valve stem 35 and on the opposite side thereof with respect to pivot connection 38 of the piston rod.

This arrangement permits valve 10 to 55 open increasingly as the pressure in supply conduit 8 tends to increase, thereby increasing the supply of exhaust elastic fluid to the exhaust header 12, and to move toward the closed position as the pressure in conduit 8 60 decreases, thereby decreasing the supply of exhaust elastic fluid. The elastic fluid supplied by conduit 8 is thus utilized to full advantage, being admitted to the auxiliary prime mover and exhaust header as rapidly

as it is supplied, while its pressure is maintained at substantially a constant value thereby.

To automatically compensate for the fluctuations in the supply of exhaust elastic fluid to the exhaust header 12 by the operation of regulator 34, the latter is also connected with the admission valve 9 and the relief valve 22 of the main prime mover to move said valves jointly with admission valve 10 in an opposite sense thereto, that is, in opposite opening or closing direction at the same time. In the present example, this connection is made through a link 44 which is pivotally connected at one end with lever 37, as indicated at 45, and which at the opposite end carries fulcrum 30 of lever 27.

Fulcrum 43 lies between the pivotal connections 36 and 45, so that the link is moved in an opposite direction from valve 10 when the latter is actuated by the regulator 34. Since the link is connected with the fulcrum 30 of lever 27 and said lever is free to turn on pivot connection 26, valves 9 and 22 are moved with the link independently of the regulator 21 in an opposite sense with respect to valve 10. As valve 10 is moved to increase the admission of elastic fluid from conduit 8, valves 9 and 22 are thus correspondingly moved to decrease the admission of elastic fluid from supply conduit 7 and the admission of excess exhaust elastic fluid to the low pressure section, and vice versa, that is, in an opposite sense from valve 10 in each case, thereby preventing fluctuations in the pressure in exhaust header 12 and heating main 13.

The relative lengths of lever 27 between 105 the pivotal valve connections therewith, determines the relative movements of valves 9 and 22. In the present example the valve connections are substantially equally spaced from fulcrum 30 so that valves 9 and 22 are moved substantially equally by pressure regulator 21, and valve 9 to a greater degree than valve 22 by regulator 34, although any other suitable arrangement may be provided, as the system of levers for connecting the 110 valves and pressure regulators herein described and illustrated represents any suitable means for performing the same function and is shown only by way of example.

The prime movers may be further controlled by a suitable speed governor responsive, for example, to the speed of shaft 11 whereby the power output from said shaft may be delivered at constant speed. A speed governor for this purpose is represented at 115 46 and is of the simple fly-weight type mounted on a bracket 47 attached to prime mover 6, and driven through a gearing 48 from shaft 11. While the governor may control the prime movers through any suit- 120 125 130

able means, it is in the present example connected with the lever system to jointly control valves 9, 10 and 22. Connection with the lever system is made through a rod 49 which at one end is connected with the governor and which at the opposite end carries the fulcrum 43 of lever 37.

The governor operates to move the rod and fulcrum downwardly correspondingly as the speed of shaft 11 increases above a certain desired normal value and to move the rod and fulcrum upwardly correspondingly as the speed of shaft 11 decreases below said normal value. As the fulcrum 43 is carried upwardly or downwardly by the governor rod, lever 37 is moved thereby in a similar manner about pivot connection 38 as a center independently of the setting of pressure regulator 34 and through connection with lever 27 by link 44 moves said lever correspondingly about pivot connection 26 as a center independently of the setting of pressure regulator 21. Valves 9 and 22 move with lever 27 and valve 10 moves with lever 37 in response to movement of the governor rod, all in the same sense with respect to each other, that is, in the same opening or closing direction at the same time, being moved in the first-named direction as the governor moves rod 49 upwardly in response to a decreased speed below normal, and being moved in the second-named direction as the governor moves rod 49 downwardly in response to an increased speed above normal.

In practice, auxiliary prime mover 6 is preferably of the high-pressure type, and through pressure regulator 34 operates to deliver exhaust elastic fluid continuously to the exhaust header 12 and heating main 13 while it is supplied with elastic fluid through conduit 8. Should the supply fail, it will be seen that valve 10 will be closed by pressure regulator 34, while valves 9 and 22 will be correspondingly opened independently of the governor 46 and of regulator 21. The high pressure section of the main prime mover then supplies the exhaust header and heating main through connection 17.

Main prime mover 5 is preferably of the low-pressure type and is arranged to automatically utilize the excess elastic fluid over that required for heating purposes, in a low pressure section in the present example, and is controlled independently of the speed governor and pressure regulator 34 by the pressure regulator 21 which operates to prevent fluctuations in the heating supply to main 13. Under certain conditions, such as those attending a failure of the supply to the auxiliary prime mover, the main prime mover is arranged to automatically supply heating elastic fluid to the heating main. The arrangement in accordance with

the invention further provides for control of the prime mover by other means, such as a speed governor, independently of the control exercised by the pressure regulators.

It is believed that the operation of the installation is clear from the foregoing description and accordingly requires no further description. While the invention has been illustrated and described in connection with a simple elastic fluid turbine installation under the direct mechanical control of piston operated pressure regulators and a speed governor, it should be understood that it is not limited thereto and may be embodied in other elastic-fluid prime-mover installations providing a main and an auxiliary prime mover adapted to operate in accordance with the invention.

What I claim as new and desire to secure by Letters Patent of the United States, is:—

1. In combination, a main elastic fluid prime mover, an auxiliary elastic fluid prime mover, a conduit for conveying elastic fluid exhausting from the auxiliary prime mover to the main prime mover, and means responsive to the pressure of the elastic fluid supplied to the auxiliary prime mover for regulating the supply of elastic fluid to both prime movers.

2. In combination, a main elastic fluid prime mover, an auxiliary elastic fluid prime mover, a conduit for conveying elastic fluid exhausting from the auxiliary prime mover to the main prime mover, a heating main connected with said conduit to receive heating elastic fluid therefrom, and means responsive to the pressure of the elastic fluid supplied to the auxiliary prime mover for regulating the supply of elastic fluid to both prime movers.

3. In combination, a main elastic fluid prime mover, an auxiliary elastic fluid prime mover, a conduit for conveying elastic fluid exhausting from the auxiliary prime mover to the main prime mover, a heating main connected with said conduit to receive heating elastic fluid therefrom, means responsive to the pressure of the elastic fluid supplied to the auxiliary prime mover for regulating the supply of elastic fluid to both prime movers, and means responsive to the pressure in the exhaust conduit for regulating the supply of elastic fluid to the main prime mover.

4. In combination, a main elastic fluid prime mover, an auxiliary elastic fluid prime mover, a conduit for conveying elastic fluid exhausting from the auxiliary prime mover to the main prime mover, a heating main connected with said conduit to receive heating elastic fluid therefrom, means responsive to the pressure of the elastic fluid supplied to the auxiliary prime mover for regulating the supply of elastic fluid to both prime movers, a speed-responsive means for regu-

lating the supply of elastic fluid to both prime movers, and means responsive to the pressure in the exhaust conduit for regulating the supply of elastic fluid to the main prime mover.

5. In an elastic fluid prime mover installation, the combination with a main prime mover, of an auxiliary prime mover, a heating supply main, an exhaust conduit for the auxiliary prime mover connected with the heating supply main and with the main prime mover whereby the latter and the heating supply main receive exhaust elastic fluid from the auxiliary prime mover, means responsive to the pressure of the exhaust elastic fluid controlling the admission of said elastic fluid to the main prime mover, and speed-responsive means for controlling the admission of elastic fluid to both prime movers.

6. In an elastic fluid prime mover installation, the combination with a main prime mover having an admission valve means, of an auxiliary prime mover, a heating supply main, an exhaust conduit for the auxiliary prime mover connected with the heating supply main and with the main prime mover whereby the latter and the heating supply main receive exhaust elastic fluid therefrom, an admission valve means controlling the admission of said exhaust elastic fluid to the main prime mover, and a pressure-responsive device connected with the first and second-named valve means to operate the same in response to changes in the exhaust elastic fluid pressure, the first-named valve means being operated thereby in an opposite sense with respect to the second-named valve means.

7. In an elastic fluid prime mover installation, the combination with a main prime mover having a high pressure section to which elastic motive fluid is supplied and a low pressure section which receives exhaust elastic fluid from the high pressure section, of an auxiliary prime mover to which elastic motive fluid is supplied, an exhaust conduit for the auxiliary prime mover connected with the low pressure section of the main prime mover to supply exhaust elastic fluid thereto jointly with the high pressure section, a relief valve means which controls the exhaust elastic fluid admission to said low pressure section, a pressure regulator for said exhaust elastic fluid connected with said relief valve means, a heating supply conduit connected with the exhaust conduit to receive heating elastic fluid therefrom, and means responsive to the speed of at least one of the prime movers for controlling the admission of elastic fluid to both prime movers.

8. In an elastic fluid prime mover installation, the combination with a main prime mover having a high pressure section pro-

vided with an admission valve means and a low pressure section which receives exhaust elastic fluid from the high pressure section, of an auxiliary prime mover to which elastic motive fluid is supplied, an exhaust conduit 70 for the auxiliary prime mover connected with the low pressure section of the main prime mover to supply exhaust elastic fluid thereto jointly with the high pressure section, a relief valve means which is movable 75 to control the admission of the exhaust elastic fluid to said low pressure section, a pressure regulator for said exhaust elastic fluid connected with the relief valve means and with the first-named valve means, means in 80 said connection which causes the first-named valve means to move in an opposite sense with respect to the relief valve means, and a heating supply conduit connected with the exhaust conduit.

9. In an elastic fluid prime mover installation, the combination with a main prime mover having a high pressure section and a low pressure section, of an auxiliary prime mover having an exhaust conduit connected 90 with the main prime mover between the high and low pressure sections thereof, a relief valve means which controls the admission of elastic fluid to the low pressure section, a heating supply conduit connected with the exhaust conduit, separate admission valve means for the prime movers, means responsive to the admission pressure of the auxiliary prime mover connected with the admission 95 valve means of both prime movers and with the relief valve means to jointly move the same, the relief and admission valve means of the main prime mover being moved thereby in an opposite sense to the admission valve means of the auxiliary 100 prime mover, and means responsive to the pressure at the admission side of the relief valve means connected with said relief valve means and the admission valve means of the main prime mover to move said valve means 110 jointly, the relief valve being moved thereby in an opposite sense to said admission valve.

10. In an elastic fluid prime mover installation, the combination with a main prime mover having a high pressure section and a low pressure section, of an auxiliary prime mover having an exhaust conduit connected 115 with the main elastic fluid prime mover between the high and the low pressure section thereof, a relief valve controlling the admission of elastic fluid to the low pressure section, a heating conduit connected with the exhaust conduit, admission valves for the main and auxiliary prime movers, a speed-responsive means connected with and controlling the relief valve and admission valves of both prime movers, said valves being moved thereby in the same sense, means responsive to the admission pressure 125 of the auxiliary prime mover controlling 130

the relief valve and admission valves of both prime movers, the relief valve and admission valve of the main prime mover being moved thereby in an opposite sense to the admission valve of the auxiliary prime mover, and means responsive to the pressure at the admission side of the relief valve connected with said valve and the admission valve of the main prime mover to move the same in an opposite sense relative to each other and independently of the admission valve of the auxiliary prime mover.

11. In an elastic fluid prime mover installation, the combination with a main prime mover having an admission valve and a high and low pressure section, of an auxiliary prime mover having an admission conduit, an admission valve therein, and an exhaust conduit connected with the main prime mover between the high and low pressure sections thereof, a heating main connected with the exhaust conduit, a relief valve controlling the admission of elastic fluid to the low pressure section, a common shaft on which the prime movers are mounted, a speed governor on said shaft operatively connected with the admission valves of both prime movers and with the relief valve, said governor operating to move said valves simultaneously and in the same sense in response to changes in speed of the shaft, a pressure-responsive means connected with the admission conduit of the auxiliary prime mover for moving the admission valve thereof simultaneously with and in an opposite sense to the admission and relief valve of the main prime mover independently of the speed governor, and a pressure-responsive

means connected with the main prime mover between the high and low pressure sections thereof for moving the admission and relief valves of said main prime mover simultaneously in an opposite sense with respect to each other and independently of the speed governor and first-named pressure-responsive means.

12. The combination with an elastic-fluid turbine having high and low pressure stages, of a heating supply conduit, a second elastic-fluid turbine which supplies exhaust elastic fluid to the low pressure stages of the first-named turbine and to said heating supply conduit, a valve controlling the admission of exhaust elastic fluid to said low pressure stages, means responsive to the pressure on the admission side of said valve connected therewith to operate the same, an admission valve for the first-named turbine connected with the first-named valve to be operated therewith in an opposite sense with respect thereto, an admission valve for the second-named turbine, pressure-responsive means for operating said valve in accordance with the supply pressure, and means connecting the last-named admission valve with the first and second-named valves whereby they are operated jointly with and in an opposite sense with respect to said last named admission valve, and a speed-responsive means controlling the first-named valve and the admission valves of both turbines independently of the pressure-responsive means.

In witness whereof, I have hereunto set my hand this 23d day of October, 1925.

ARTHUR ROSCH.
